UNITED STATES PATENT OFFICE.

FRANÇOIS MAURON, OF BADEN, SWITZERLAND, ASSIGNOR TO AKTIENGESELLSCHAFT BROWN, BOVERI AND CIE., OF BADEN, SWITZERLAND.

VIBRATING CONTACT REGULATOR.

Application filed December 19, 1927, Serial No. 241,219, and in Germany August 30, 1926.

This invention relates to automatic voltage or other regulators designed to operate on the shunt circuits of dynamos and alternators and is particularly concerned with 5 regulators of the vibrating contact type in which a resistance in the field of the generator or exciter is periodically short-circuited.

The main object of the invention is the provision of a voltage or other regulator of 10 the above type capable of dealing with comparatively large field currents and at the same time giving very close regulation.

A further object of the invention is the provision of a regulator of the type described 15 in which a high degree of precision in operation is combined with simple construction. Other and further objects will be pointed out or indicated hereinafter or will be apparent to one skilled in the art upon an understanding of the invention or its employment 20 in practice.

In the drawing accompanying this specification are shown two different arrangements in which the invention may be embodied, but it is to be understood that these 25 are presented for purpose of illustration only and are not to be accorded any interpretation having the effect of limiting the claims short of the true and most comprehensive 30 scope of the invention in the art.

In the drawing:

Figure 1 is a diagrammatic view of voltage regulating apparatus for a self-excited shunt-wound direct-current dynamo.

35 Figure 2 is a diagrammatic view of a similar apparatus applied to the voltage regulation of an alternator.

Automatic voltage regulators of the vibrating contact type as hitherto known in the 40 art may be divided into two classes, one in which a single resistance is periodically cut in and out of circuit and the other in which the resistance is divided into sections which are successively cut in according to the requirements. Regulators of the first class can 45 only be used when the excitation power is small since their range of application is limited by the sparking at the contacts. Regulators of the second class are suitable for 50 larger powers but cannot be made to give very close regulation. In addition they are either complicated in construction or must be provided with special damping arrange-

ments if satisfactory operation is to be secured.

The present invention provides a voltage regulating apparatus which does not suffer from the disadvantages enumerated for the two types above, while at the same time retaining the good points of both. This is attained by a combination of main and auxiliary contacts cooperating in sliding or like relationship with the regulating resistance, the two contacts being separated by a small number of resistance steps and coupled together. The main contact gives coarse regulation and the auxiliary contact in conjunction with a trembler relay provides the fine regulation required. The arrangement is such that in addition to the section of resistance which is permanently bridged by the main contact there is a further section which is intermittently short-circuited, this second resistance section lying between the main and auxiliary contacts and bearing a suitable relation to the total resistance of the exciter field circuit. This results in uniform loading of the vibrating contacts throughout the whole range of regulation.

An understanding of the invention will be 80 most readily obtained from a consideration of the examples illustrated in the drawing accompanying this specification.

In Figure 1 of the drawing the reference character 1 denotes the armature and 2 the field of a dynamo, the field 2 being connected in shunt to the armature through the regulating resistance 3. The latter is provided with contacts 4 and 5 which are arranged in sliding or other variable relationship to the 85 resistance. These movable contacts are attached to the core 6 which is surrounded by windings 7 and 8, the former of which is connected in parallel with the armature of the dynamo, while the latter is connected across the contacts 10 and 11 of the trembler relay. The trembler contact 11 is attached to the moving armature 14 and is attracted by the relay core 9 against the action of the spring 15. The core 9 is provided with two 90 windings of which one (12) is connected to the terminals of the dynamo 1 and the other (13) to the contacts 10 and 11 of the trembler relay.

The operation of the regulator is as follows:—When the E. M. F. developed by the

dynamo 1 is zero there will be no current flowing in the coils 7, 8 and 12. The upper portion of the regulating resistance 3 is short-circuited by the contact 4 and the lower portion 5 which lies between the contacts 4 and 5 is likewise short-circuited by the contacts 10 and 11 of the trembler relay which are held together by the spring 15. The contacts 4 and 5 will take up their lowest position owing to the weight of the core 6 to which they are attached. As soon, however, as the voltage at the terminals of the dynamo 1 reaches its prescribed value, the pull of the magnet 9 exactly balances that of the spring 15, although the contacts still remain closed. If the voltage of the dynamo exceeds the prescribed value by a small amount, the electromagnetic pull exerted by the coil 12 will overcome the pull of the spring 15 and the contacts 10 and 11 will be separated with the result that the section of resistance lying between contacts 4 and 5 is inserted in the dynamo field circuit. Simultaneously with the opening of the trembler relay contacts 10 and 25 11 the voltage of the dynamo will drop to below the normal and the spring 15 being now able to overcome the pull of the magnet 9 will cause the contacts to close. The voltage of the dynamo will thereupon rise once more and the sequence of operations described above will be repeated; the opening and closing of the contacts 10 and 11 taking place so rapidly that the armature 14 is given a trembling motion. The section of resistance lying 30 between the contacts 4 and 5 is thus alternately cut into the field circuit and short-circuited. Let the resistance of this section be r , the time during which it is in circuit with the field 2 be z , and the time during which it is short-circuited be $t-z$. The same effect 35 may be considered as being produced by a resistance of appropriate size permanently connected in circuit, this resistance representing the "effective" value of the resistance between the contacts 4 and 5. Let this effective resistance be denoted by R . Then by varying the ratio

$$\frac{t-z}{z} = \frac{\text{duration of short-circuit}}{\text{duration of break}}$$

the value of the effective resistance R is also varied. Thus if a change in the trembling motion of the contact 11 causes an increase in the effective resistance, the current in the field circuit will be reduced although not in the same proportion as the increase in R . This is owing to the fact that the change in the total resistance of the field circuit is very small. As a result, the voltage across the contacts 10 and 11 increases and causes an increased current to flow in the winding 8. When the voltage across the above contacts has reached a certain value, the ampere-turns of the coil 8 will be sufficient to cause an upward movement of the core 6 carrying the

contacts 4 and 5, this movement varying the resistance step by step. Immediately the first step has been traversed the trembler relay will alter the ratio

$$\frac{\text{duration of short-circuit}}{\text{duration of break}}$$

and consequently the voltage of the dynamo 1 with the result that the ampere-turns of the coil 8 are again reduced. If the voltage at the terminals of the dynamo falls, the sequence of operations takes place in the reverse order. In order to prevent the core 6 being moved with every trifling variation of the voltage between the contacts 10 and 11, and to arrange for step by step regulation the regulating contacts 4 and 5 are made wide enough to bridge the gaps between a series of contacts which form tapping points on the resistance 3 in the well-known manner. Other known means may be employed for producing this step-by-step variation.

The chief advantage of the arrangement described above is that the fine regulation is performed through the medium of a trembler relay which gives very close regulation. The coil 7 shown in the figure is not an essential feature of the invention and may be dispensed with if the coil 8 is given sufficient turns to produce the required lifting effort alone.

An arrangement for the voltage regulation of an alternator is shown in Figure 2 of the drawing. The reference character 29 there-in denotes an alternator having a field winding 16 which is supplied by an exciter 17, 18. The field circuit of this exciter contains a resistance 20 which is provided with adjustable contacts similar to those used for the resistance 3 in Figure 1 aforesaid. These contacts are carried on a core 19 arranged in movable relationship with the coil 30 which is energized with direct-current from the exciter circuit. The arrangement shown in Figure 2 differs chiefly from that of Figure 1 in the provision of a special relay which controls the trembling action of the contacts 22 and 23. The coil 27 is connected to two of the alternator terminals and is provided with a core 26, its function being to vibrate the diaphragm 25 carrying the contact 24. The natural frequency of this diaphragm is approximately equal to that of the alternating current with which the coil 27 is energized and the contact 24 will therefore execute a vibration of definite frequency and with a certain amplitude. The contact 23 is flexibly connected to the core 21 by a spring 22, and will therefore commence to follow the motion of the contact 24. As soon as the voltage at the alternator terminals exceeds the normal or rated value the core 21 is drawn upwards by the coil 28, thus momentarily separating the contacts 23 and 24. The momentary separation of these contacts inserts the sec-

tion lying between the contacts on the resistance 20 into the field circuit of the exciter. This results in a variation of the ratio

$$5 \quad \frac{\text{duration of short-circuit}}{\text{duration of break}}$$

as with the arrangement in Figure 1, the ratio being increased or decreased according to the direction of the voltage change.

10 Under normal voltage conditions the core 21 is held in equilibrium by the coil 28, and is raised or lowered according to the change in the voltage.

The method of regulation described above 15 is not limited to voltage but may be extended to current, power, and power factor regulation. The regulator may be given a compound characteristic and means for compensating disturbing influences may be provided. 20 The connection between the regulator and generator may be made through potential and current transformers if the conditions require this.

Having now described my invention, what 25 I claim as new and desire to secure by Letters Patent is:—

1. A vibrating contact regulator for electrical machines and systems comprising a regulable resistance, a main and an auxiliary 30 contact at a fixed distance apart but slidably adjustable on said regulable resistance, said contacts being adapted to be operated in concert at a fixed distance apart, and spanning part of said regulable resistance and a pair 35 of vibrating contacts controlled by the quantity it is desired to regulate, connected one to said main and the other to said auxiliary contact.

2. A vibrating contact regulator for electrical machines and systems comprising, in 40 combination, a step-by-step resistance for performing the required regulation, main and auxiliary contacts operating at a fixed distance apart in adjustable relation with said 45 resistance, a pair of vibrating contacts con-

nected respectively to the said main and auxiliary contacts, means responsive to the quantity to be regulated for effecting the vibration of said vibrating contacts and means responsive to the voltage existing between 50 said vibrating contacts for adjusting the position of the aforesaid main and auxiliary contacts relative to the step-by-step resistance.

3. A vibrating contact regulator for voltage regulation of direct-current machines 55 comprising in combination, a step-by-step resistance controlling the field current of the machine, main and auxiliary contacts operating at a fixed distance apart in adjustable relation with said resistance, a pair of vibrating contacts connected respectively to said main and auxiliary contacts, means responsive to the voltage of the machine for effecting the vibration of said vibrating contacts and means responsive to the voltage existing 60 between said vibrating contacts for adjusting the position of the aforesaid main and auxiliary contacts relative to the step-by-step resistance.

4. A vibrating contact regulator for direct-current machines and systems comprising, in combination, a step-by-step resistance adapted to control the field of the machine, main and auxiliary contacts operating at a fixed distance apart in adjustable relationship with 70 said resistance, a pair of vibrating contacts connected respectively to the said main and auxiliary contacts, means responsive to the quantity to be regulated for effecting the vibration of said vibrating contacts, a winding 75 adapted to influence the action of said vibrating contacts connected between the aforesaid main and auxiliary contacts, and means responsive to the voltage existing between said 80 vibrating contacts for adjusting the position of the said main and auxiliary contacts relative to the step-by-step resistance.

In testimony whereof I have signed my name to this specification.

FRANÇOIS MAURON.
